CLAIM

The ornamental design for a contact lens, as shown and described.

DESCRIPTION

FIG. 1 is a front elevational view of a contact lens of the present invention;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a fragmentary front elevational view thereof taken from area VII of FIG. 1, the fragmentary rear elevational view being a mirror image to the fragmentary front elevational view;

FIG. 8 is a fragmentary right side elevational view thereof taken from area VIII of FIG. 3, the fragmentary left side elevational view being a mirror image to the fragmentary right side elevational view; and,

FIG. 9 is a cross-sectional view thereof taken from area IX of FIG. 1.

The contact lens is used for the correction of Presbyopia.
